UNITED STATES PATENT OFFICE.

ANDREW CAMPBELL, OF BROOKLYN, ASSIGNOR TO JOHN McLOUGHLIN
AND EDMUND McLOUGHLIN, OF NEW YORK, N. Y.

MOUNTING FORM-ROLLERS FOR PRINTING-PRESSES.

SPECIFICATION forming part of Letters Patent No. 282,956, dated August 14, 1883.

Application filed February 20, 1883. (No model.)

To all whom it may concern:

Be it known that I, ANDREW CAMPBELL, a citizen of the United States, and a resident of Brooklyn, Kings county, New York, have invented certain Improvements in Mounting Form-Rollers for Printing-Presses, of which the following is a specification.

My invention relates to an improved bearing for the journals of an inking form-roller for printing-presses.

The object of my invention is to provide a bearing that may be adjusted vertically with ease, and which may be turned, when worn, on its side, or inverted.

15 Heretofore in constructing and mounting the boxing for the ends of the form-rollers it has been customary, so far as I am aware, to provide the square or angular bodies of the boxes with lateral flanges, and to arrange said 20 boxes to slide in vertical slots or forks in the frames. These boxes have been provided with adjusting-screws to regulate the height at which the roller is intended to stand, normally, with respect to the form; but, so far as 25 I am aware, no means have been provided to prevent the adjustment from being disturbed by the jarring of the press. This difficulty I seek to overcome by providing the box with pendent flanges at its ends, which are adapted 30 to embrace the square or polygonal head of the adjusting-screw so closely as to prevent the screw from being turned without lifting the box, as will be more fully hereinafter explained.

35 I provide a long box for the roller-spindle, whereby a considerable extent of bearing-surface is furnished, and providing this box with a square to rest in a fork in a bracket on the press-frame, said square being flanked by two 40 collars formed on the box. The square on the box rests on the square or polygonal head of an adjusting-screw in the fork of the bracket, the head of which is so closely embraced by the collars on the box, when the latter is in 45 place, that it cannot be turned or disturbed by accident, and only by raising the box high enough for the collars to clear the head. When the box becomes worn on one side, which it will not be for a long time, by reason of its 50 length, it may be slipped off the spindle and

turned over. The collars embrace the jaws of the fork on the bracket, so that the box cannot play endwise, and it is thus limited strictly to a vertical movement. The vertical adjustment of the box may be necessary in doing 55 fine work many times during the day, as the rollers are being changed continually, and the shrinkage is always going on until the roller is worn out. For this the ordinary forms of roller-mounting do not furnish adequate 60 provision.

In the drawings, which serve to illustrate my invention, Figure 1 is a side view of the bearing, showing the boxing in transverse section on line 1 1 in Fig. 2. Fig. 2 is a sectional 65 elevation taken substantially on line 2 2 in Fig. 2. Fig. 3 is an elevation on a smaller scale, illustrating the application of my invention to a swivel-bearing for shifting angle-rollers, employed mainly in distributing. 70

A is the bearing-bracket, which may be recessed at a to receive a flange on the press-frame, as indicated in dotted lines in Fig. 2. The attachment of the bracket is effected by means of a screw or bolt, as also indicated in 75 said figures.

The bracket A is provided with two upright jaws, b b, which embrace a square, c, formed on the box B. The box is also provided with two collars, d d, which embrace the jaws b, 80 and prevent any movement endwise of the box.

The box is provided with a bore, e, to receive the spindle or journal of the form-roller, and four oil-holes, g, in the sides of the square c. 85 Whichever side of the square is uppermost, an oil-hole is provided to receive the lubricant. The holes at the sides are stopped by the jaws b, (see Fig. 1,) and the hole at the bottom is stopped by the head of an adjusting-screw, C, 90 on which the box rests. This screw screws into the bracket at the bottom of the recess between the jaws, and has a flat square head, upon which the square on the box rests. The head of this screw is about equal in width to the thickness of the jaws b, so that it will be closely embraced by the collars d d when the box is in 95 place, and be thus prevented from turning, as will be well understood.

When it is desired to raise or lower the box, 100

it is lifted out or raised up, and the screw C adjusted to the proper elevation.

When the box becomes worn it may be lifted out and turned over. When worn out it may be renewed without the necessity of renewing the bracket. As the boxing cannot move laterally nor longitudinally, it follows that it must play in a truly vertical plane, and as the box is entirely independent of the bracket, I 10 may make it quite long, as shown in Fig. 2, so as to give to the roller-journal a long bearing.

The construction shown in Figs. 1 and 2 is adapted for rollers which extend across the 15 form or distributing-table at right angles to the line of travel of the bed, and which have only a vertical play. For "angle-rollers," so called, which extend obliquely across the form or table, and which are sometimes arranged to vary their angles by a movement at one end, I employ 20 the construction shown in Fig. 3. In this construction the jaws b are constructed separately from the bracket, and provided with a shank or spindle, h, which rests in a socket in the bracket or holder A. In either construction 25 the box B and its adjusting-screw C are the same.

I do not claim, broadly, an adjusting-screw arranged under a boxing to regulate its height. This is a well-known device. But it will be observed 30 that when the box B rests on the square or polygonal head of the screw the latter is prevented from turning until the box is lifted. This I believe to be new.

Having thus described my invention, I 35 claim—

1. The combination, with the non-rotative box provided with pendent collars, and the bracket provided with jaws to receive it, of the square-headed adjusting-screw, with its head arranged to take between the collars on the 40 box, substantially as and for the purposes set forth.

2. The box B, provided with a square, c, and collars d, in combination with the bracket provided with jaws b to embrace the square c, 45 and the adjusting-screw C, all arranged to operate, substantially as set forth.

3. The box B, provided with the square c, and with collars d, in combination with the bracket provided with jaws b, and the adjusting-screw C, the head of which is arranged to be closely embraced by the collars d on the 50 box, substantially as and for the purposes set forth.

4. As a bearing for the roller of a printing-press, the box B, provided with a square, c, and collars d, in combination with the bracket provided with jaws b, all constructed and arranged substantially as and for the purposes 55 set forth.

In witness whereof I have hereunto signed my name in the presence of two subscribing witnesses.

ANDREW CAMPBELL.
